(57) **CLAIM**

The ornamental design for an electronic drum, as shown and described.

DESCRIPTION

FIG. 1 is a front perspective view of the electronic drum according to the present invention;

FIG. 2 is a front view thereof;

FIG. 3 is a rear view thereof;

FIG. 4 is a first side view thereof;

FIG. 5 is a second side view thereof;

FIG. 6 is a first end view thereof; and,

FIG. 7 is a second end view thereof.

Broken lines in the drawing figures show environmental structure only, and form no part of the claimed invention.
